CAP RETAINER FOR DISPENSING TUBES

Louis M. Rausch, Neenah, Wis.

Application August 12, 1940, Serial No. 352,321

5 Claims. (Cl. 221—60)

This invention relates to closures for dispensing tubes and more particularly to a cap retaining device especially designed for use on tubes containing tooth paste and the like.

The object of the invention is to provide a cap retainer of simple and inexpensive construction capable of being quickly attached to the neck of a tube of tooth paste and which will support the cap on the tube while applying paste to a tooth brush so as to prevent accidental displacement or loss of said cap.

A further object of the invention is to provide a cap retainer comprising pivotally connected members, one of which is provided with means for detachable engagement with the neck of a dispensing tube and the other with means for rotatably receiving the cap or closure of said tube so as to permit the cap to be unscrewed and swung laterally to open position to allow discharge of tooth paste or swung inwardly to closed position in threaded engagement with the discharge nipple of said tube.

A still further object of the invention is generally to improve this class of devices so as to increase their utility, durability and efficiency as well as to reduce the cost of manufacture.

In the accompanying drawing forming a part of this specification and in which similar numerals of reference indicate corresponding parts in all the figures of the drawing:

Figure 1 is a side elevation of a portion of a tube of tooth paste showing my improved cap retainer in position thereon with the cap in closed position.

Figure 2 is a similar view showing the cap swung laterally to open position to permit discharge of the tooth paste.

Figure 3 is a top plan view showing the cap in open position, and

Figure 4 is a perspective view of the cap retainer removed from the tube.

The improved device forming the subject-matter of the present invention may be used in connection with any type or style of dispensing tube, and by way of illustration is shown applied to a standard tube of tooth paste, in which 5 designates the body of the tube and 6 the threaded neck or discharge nipple.

The device is preferably formed of resilient wire and comprises coacting pivotally connected members 7 and 8, one of which is adapted to rotatably receive the cap or closure 9 of the tube 5 and the other the threaded nipple 6. The member 7 is formed of a single length of wire bent upon itself to form a substantially circular socket

10 adapted to rotatably receive the depending flange 11 of the cap 9, the wire strands being then bent laterally at 12 and forwardly to form a contact finger 13, the end of which is deflected downwardly at 14 for engagement with the top of the cap 9. After the socket 10 is formed, the ends of the wire are bent laterally in opposite directions to form horizontal pins 15 terminating in finger engaging buttons 16. The member 8 of the cap retainer is also preferably formed of a single length of wire bent to form an intermediate loop 17 adapted to fit around the threaded nipple 6 of the tube 5 and terminating in a downwardly curved finger 18 adapted to bear against the adjacent end of the tube 5. After the loop 17 is formed, the ends of the wire are crossed at 19 and extended in opposite directions to form intersecting arms 20 having their ends bent upwardly and thence downwardly to form loops 21 which fit over the adjacent pins 15 and in conjunction therewith form a pivotal connection or hinge for moving the cap or closure 9 to open and closed positions.

It will here be noted that, inasmuch as the cap retainer is formed of spring wire, the walls of the loop 17 will yieldably engage the nipple 6 and thus detachably retain the device in position on the dispensing tube. It will, furthermore, be noted that the curved walls of the loop 10

also yieldably engage the cap 9 and, inasmuch as the finger 13 bears against the top of the cap, said cap is held from accidental displacement while at the same time it is free to rotate within the loop. In positioning the device on a tube

35 of tooth paste, the loop 17 is expanded by exerting a slight inward pressure with the thumb and finger on the upstanding portions 22 of the arms 20, thereby permitting the loop 17 to fit over the nipple 6. When inward pressure on the upstanding portion 22 is relieved, the inherent resiliency of the wire will cause the walls of the loop 17 to

40 resiliently engage the discharge nipple 6. By pressing inwardly on the finger engaging buttons 16, the loop 10 may be expanded so as to permit said loop to fit over the cap 9 and beneath the shoulder thereof, as best shown in Figure 1 of the drawing. If desired, however, both the members 7 and 8 may be expanded simultaneously by exerting an inward pressure on the finger buttons 16.

45 When this is done, the initial inward pressure exerted on the buttons 16 will first expand the loop 10 and a further inward pressure thereon will expand the loop 17.

When it is desired to brush the teeth, the cap 9 is rotated on the threads 6 to released po-

sition, after which said cap is swung laterally to the position shown in Figure 2 of the drawing, and in which position the paste may be readily discharged through the nipple 6. After cleaning the teeth, the cap is swung inwardly to closed position and said cap manually rotated until the threads on the cap engage the threads on the nipple 6 and in which position the cap will prevent the escape of dentifrice from the tube.

It will thus be seen that there is provided a 10 comparatively simple and inexpensive device which may be quickly attached to or detached from any style of dispensing tube and which will support the cap or closure of the tube at one side of the discharge opening therein when applying 15 dentifrice to a tooth brush so that liability of the cap becoming accidentally displaced and lost is reduced to a minimum.

It will, of course, be understood that the devices 20 may be made in different sizes and shapes and constructed of any suitable material without departing from the spirit of the invention.

Having thus described the invention, what is claimed as new is:

1. The combination with a dispensing tube having a discharge nipple and closure cap, of a cap retainer including an upper member having a socket adapted to rotatably receive said cap and having portions thereof intersecting and extended in opposite directions to form pins terminating in finger engaging buttons, and a lower member fitting over and yieldably engaging the nipple of the tube and provided with intersecting portions terminating in arms having eyes receiving said pins adjacent said buttons to permit the upper member to be swung laterally with respect to the lower member.

2. The combination with a dispensing tube having a discharge nipple and closure cap, of a cap retainer including an upper member formed of a single length of wire having its intermediate portion bent to form a socket adapted to rotatably receive said cap and having intersecting end portions extending in opposite directions to form pins terminating in finger engaging buttons, a lower member formed of a single length of wire having its intermediate portion bent to form a socket adapted to yieldably engage the discharge nipple of the tube and provided with intersecting portions terminating in arms having eyes fitting over said pins in spaced relation to said buttons to permit the upper member to be swung laterally with respect to the lower member.

3. The combination with a dispensing tube having a discharge nipple and a closure cap therefor, of a cap retainer comprising an upper expandable member having a socket adapted to rotatably receive the cap of the tube and provided with an overhanging finger adapted to bear against the top of said cap, said upper member having portions thereof extending in opposite directions to form horizontal pins, and a lower member provided with a socket adapted to receive and resiliently grip the nipple and provided at one end thereof with a finger for engagement with the adjacent end of the tube, the other end of the lower member having portions extending in opposite directions to form angular arms terminating in eyes fitting over the pins to permit the upper member together with the cap to be swung laterally to open and closed positions.

4. A cap retainer for dispensing tubes comprising coacting pivotally connected upper and lower members, the upper member being formed of a single length of wire bent to form an expandable socket adapted to rotatably receive the closure cap of a dispensing tube, the wire after the socket is formed being crossed and extended in opposite directions to form pins terminating in finger engaging buttons, the lower member being also formed of a single length of wire having its intermediate portion bent to form an expandable socket adapted to fit over the nipple of a dispensing tube and provided with intersecting arms terminating in eyes fitting over the pins adjacent said buttons.

5. A cap retainer for dispensing tubes comprising an upper member formed of a single length of resilient wire bent upon itself to form an expandable socket adapted to rotatably receive the cap of a dispensing tube, the wire at one side of the socket being bent to form an overhanging finger for engagement with the top of said cap and the wire at the other side of the socket being crossed and extended in opposite directions to form pins and a lower member formed of a single length of resilient wire bent upon itself to form an expandable socket adapted to fit over the discharge nipple of said tube, the wire on one side of the last-mentioned socket being bent to form a finger for engagement with the adjacent wall of the tube and the wire on the other side of the last-mentioned socket being bent in opposite directions to form intersecting arms terminating in eyes receiving said pins.

LOUIS M. RAUSCH.
